Melville W. Clement and Harry L. Stevenson,
Jamestown, N. Y.

Application March 9, 1953, Serial No. 23,959

Term of patent 14 years

(Cl. D33—2)

To all whom it may concern:

Be it known that we, Melville W. Clement and Harry L. Stevenson, citizens of the United States, residing at Jamestown, State of New York, have invented a new, original, and ornamental Design for an End Support for Books and the like, of which the following is a specification, reference being had to the accompanying drawing, forming a part thereof.

Fig. 1 is a top plan view of an end support for books and the like, showing our new design;

Fig. 2 is a front elevational view thereof;

Fig. 3 is an outer end view thereof;

Fig. 4 is an inner end view thereof; and

Fig. 5 is a rear elevational view thereof.

We claim:

The ornamental design for an end support for books and the like, as shown.

MELVILLE W. CLEMENT.
HARRY L. STEVENSON.
